WINDOW LOCK

Joseph Barry, Richmond Hill, N. Y.

Application January 20, 1950, Serial No. 139,627

5 Claims. (Cl. 292—63)

1

This invention relates to locking devices and more particularly to an auxiliary window lock to work in conjunction with the ordinary window sash lock which is conventional with window construction. This auxiliary lock prevents relative movement between the upper and lower sash units of the window.

An object of the invention is the provision of a novelly constructed window lock which may be quickly and easily operated from the inside of a building but which when in its locked position will be fool-proof in its prevention of unauthorized entry into the building through the window. The particular design of the various working parts of this lock is such that the device is not receptive to the many burglary techniques which continuously bring about the loss of property through crime.

Another object of my present invention is to provide a locking device which can be easily applied to a window and when in place will not be unsightly.

Still further advantages of the invention lie in the fact that the device is simple in nature and inexpensive to manufacture, yet at the same time extremely sturdy in construction and effective in use.

These and other objects and advantages of the present invention will become apparent from the following description and the accompanying drawing in which:

Figure 1 is a perspective view of the invention installed for use on a window.

Figure 2 is a plan view of the window lock in the operative position.

Figure 3 is a view of the lock in the inoperative position with the device shown in longitudinal section to show its interior structure.

Figure 4 is a side elevation of the locking bar.

Figure 5 is a perspective view showing one form of pivot nut for use with the device.

Figure 6 is a perspective view of a modification of the pivot nut.

Similar reference characters in the several figures represent similar parts.

For many years the conventional sash lock commonly found on vertically movable windows has been found to be completely ineffective against skilled housebreakers. It is a simple operation, for instance, to spread the window jambs apart with a screw driver and then inserting a pen knife to slide the locking element in an "off" position so that the sash panels may be moved in relation to one another to permit entry through the window. With this in mind the present in-

2

vention has been devised to offer assurance that once a window is locked in a closed position, opening of the same is virtually impossible from the outside.

As will be seen from Figure 1 of the drawing, the window lock generally designated by the numeral 10 is of necessity small in size in order that it may be applied to the exposed surfaces of the upper window sash. The lock base 11 consists of a frame member having right-angle flanges 12 and 13. Flange 12 is provided with a plurality of drilled apertures 14 adapted to receive screws for use in securing the frame to the surface 15 of the vertical side member of the upper sash section. As best seen in Figure 2 apertures 14 are countersunk at their exposed ends to enable the fastening screw heads to lie flush with face 16 of flange 12 so that the closely adjacent upper and lower sash sections will pass freely without obstruction by protruding screwheads.

From the apex of base 11, flange 13 extends along face 17 of the side member toward the glass pane 18 of the upper sash. For the purpose of illustration I have shown face 17 as a flat surface normal to the plane of the window sash. However, it will be readily seen that if a window contains fanciful moulding instead of the flat surface shown at 17, then it is but necessary to offset flange 13 toward the center of the window to allow clearance for the moulding. It is not only unnecessary but also undesirable to provide screw holes in flange 13 since the working space permitted by the glass pane 18 would make installation of the device a difficult task. Affixation of flange 12 alone is sufficient to obtain proper securing of the lock to the window sash.

The locking bar 19 utilized in the present invention consists of a cast plate retained adjacent to the frame 11 by means of a connecting pivot shaft 20. Shaft 20 is basically of cylindrical stock having a square end portion 21 adapted to be snugly received by a mating aperture 22 located in the lower half of flange 13. The similarly irregular configurations of end 21 and aperture 22 prevent relative rotation between the lock frame 11 and shaft 20 and lateral relative movement is likewise prevented by shoulder 23 (Fig. 5) and rivet head 24 (Fig. 3) formed on the shaft and abutting the opposing faces of flange 13.

The outer end of shaft 20 carries a rotatable pivot nut 25 which is retained on the shaft by a rivet head 26. The specific shaft of the pivot

nut may vary and for this reason I have shown two different modifications of this element. In Figure 5 the nut 25 appears as a rounded knob having a knurled cylindrical periphery 27. One face 28 of the nut is provided with a peg 29 acting as a bearing finger to cooperate with a cam track as will be later explained.

The cast-pivot nut 25a shown in Figure 6 has a flat elongated body portion having a protruding bearing finger 29a formed at one end. The remaining portions of the pivot shaft 20a are identical with those of the form shown in Figure 5.

The pivot shaft 20 penetrates the locking bar by means of an opening 30 formed in the bar and being of greater diameter than shaft 20. This latter feature enables the locking bar to cant relative to the axis of the pivot shaft when the bar is moved to its off position as shown in Figure 3.

Concentrically with opening 30 is formed a countersunk recess 31. This recess receives a portion of a spiral spring 32 the end of which abuts on a stepped shoulder 33 between recess 31 and the opening 30. The opposite end of spring 32 abuts the face 28 of the pivot nut to hold the spring in compression.

The previously mentioned cam track is in the form of a recess 34 milled in the outer surface 35 of the locking bar and having an inclined bottom 36 which acts as a cam when confronted by the rotating bearing finger 29 of the pivot nut.

In order to adequately explain the function of the above camming action, it is first necessary to discuss the significance of the offset section 37 formed on that face of the locking bar opposite to the recessed face 35. Offset 37 is provided on what might be termed the forward half of the locking bar and the halves of the bar being of different thickness produce a stepped-down effect leaving a contact face 38 which extends the width of the locking bar. The sash lock will be seen in its "off" or open position in Figure 3 of the drawing and in this position the locking arm is raised so that offset 37 lies adjacent the outer surface of flange 13 of the frame member. However, when the lock is closed the spring causes offset 37, then in a vertical position, to snap over the face of flange 12 (Figures 1 and 2) and from this point on upward rotation of the locking bar is impossible without first manually moving the bar laterally away from the frame member 11 to allow offset 37 to clear flange 12 of the frame.

As added security to the above described snap action locking function the cooperating pivot nut and cam may be used to positively hold the locking bar against lateral movement brought about by the insertion of a knife or other appropriate tool between adjacent faces of the window sash. The cam 36 has a high point and a low point. Pivot nut 25 being held against outward movement by the rivet head 26, may be rotated to selectively position its bearing finger on either the high or low point on the cam. From Figure 3 it will be seen that unless the low point of the cam is opposite the bearing finger, locking bar 19 may not be moved laterally away from its locked position relative to the frame 11.

At this point it is important to note that the positioning of spring 32 between the locking bar and pivot nut provides an equalization of spring tension on each of these members. This is essential because when the bottom section of the window is rocked or forced by a would-be housebreaker the pivot nut will remain in its correct

position on the high point of the cam surface thereby rigidly holding the locking bar against lateral movement.

From the foregoing description of the various elements of the invention it is believed that the operation of the device will be readily apparent. To lock the upper and lower sash panels of the window in place the locking bar 19 is rotated forwardly and downwardly until the offset portion snaps into closed position over the forward face of the frame member 11. In this position the lower edge 39 of the bar will be horizontal and act as a stop preventing upward movement of the lower sash panel. Then to lock the bar in a closed position the pivot nut is rotated clockwise to bring the bearing finger upon the high point of the cam recess formed in the locking bar. Thus it will be seen that until the pivot nut is once again turned to release the cam the locking device may not be released even by the cleverest of housebreaking techniques.

Of course it will be readily seen that this same device may be applied to a bedroom window in such a manner as to permit the window to be slightly open for purposes of ventilation. For this arrangement it is but necessary to attach the frame member the desired distance above the point of application shown in Figure 1 of the drawing.

From the above detailed explanation of the invention it will be seen that I have devised a simple locking mechanism which presents the first successful challenge to unlawful entry through windows. The sash lock possesses every desirable advantage in the way of manufacturing and installation simplicity and fool-proof effectiveness.

While I have shown and described a preferred form of my invention, it will be understood that variations in details of form may be made without departure from the invention as defined in the appended claims.

I claim:

1. A device for preventing relative movement between upper and lower window sashes comprising an angle frame having flanges disposed at right angles to each other, said frame being adapted to be secured to the upper sash, a shaft attached at one end to said frame, a locking bar adjacent one of said flanges and supported by said shaft, said bar being rotatable relative to the frame to a locking position, an offset portion on said bar engageable with the other of said flanges when the bar is in said locking position, a knob rotatably mounted on the free end of said shaft and having an inwardly extending finger thereon, a cam surface formed on said locking bar cooperating with said finger to clamp the bar in engagement with said other flange of the frame, and means mounted on the shaft for laterally urging the locking bar toward the frame.

2. A device for preventing relative movement between upper and lower window sashes comprising an angle frame having flanges disposed at right angles to each other, said frame being adapted to be secured to the upper sash, a shaft attached at one end to said frame, a locking bar adjacent one of said flanges and supported by said shaft, said bar being rotatable relative to the frame to a locking position, an offset portion on said bar engageable with the other of said flanges when the bar is in said locking position, a knob rotatably mounted on the free end of said shaft and having an inwardly extending finger thereon, a cam surface formed on said locking bar coop-

erating with said finger to clamp the bar in engagement with said other flange of the frame, and means mounted on the shaft between the knob and bar for laterally urging the locking bar toward the frame.

3. A device for preventing relative movement between upper and lower window sashes comprising an angle frame having flanges disposed at right angles to each other, said frame being adapted to be secured to the upper sash, a shaft attached at one end to said frame, a locking bar adjacent one of said flanges and supported by said shaft, said bar being rotatable relative to the frame to a locking position, an offset portion on said bar engageable with the other of said flanges when the bar is in said locking position, a knob rotatably mounted on the free end of said shaft and having an inwardly extending finger thereon, a cam surface formed on said locking bar cooperating with said finger to clamp the bar in engagement with said other flange of the frame, and a spring mounted on the shaft for laterally urging the locking bar toward the frame.

4. A device for preventing relative movement between upper and lower window sashes comprising an angle frame having flanges disposed at right angles to each other, said frame being adapted to be secured to the upper sash, a shaft attached at one end to said frame, a locking bar adjacent one of said flanges and supported by said shaft, said bar being rotatable relative to the frame to a locking position, an offset portion on said bar engageable with the other of said flanges when the bar is in said locking position, a knob rotatably mounted on the free end of said shaft and having an inwardly extending finger thereon, a cam surface formed on said locking bar cooperating with said finger to clamp the bar in engagement with said other flange of the frame, and a spring mounted on the shaft for laterally urging the locking bar toward the frame.

bar in engagement with said other flange of the frame, and a spring mounted on the shaft between the knob and bar for laterally urging the locking bar toward the frame.

5. A device for preventing relative movement between upper and lower window sashes comprising an angle frame having flanges disposed at right angles to each other, said frame being adapted to be secured to the upper sash, a shaft attached at one end to said frame, a locking bar adjacent one of said flanges and supported by said shaft, said bar being rotatable relative to the frame to a locking position, an offset portion on said bar engageable with the other of said flanges when the bar is in said locking position, a knob rotatably mounted on the free end of said shaft and having an inwardly extending finger thereon, a cam surface formed on said locking bar cooperating with said finger to clamp the bar in engagement with said other flange of the frame, and a spring surrounding the shaft and having its ends bearing on the knob and bar for laterally urging the locking bar toward the frame.
